C. Fisher,

Burning Hydrocarbon.

No 67,108.

Patented July 23, 1867.

UNITED STATES PATENT OFFICE

CLARK FISHER, OF TRENTON, N. J., ASSIGNOR TO SIMON STEVENS, OF NEW YORK CITY; AND SIMON STEVENS ASSIGNOR TO CLARK FISHER.

IMPROVEMENT IN MODES OF BURNING HYDROCARBON LIQUIDS.

Specification forming part of Letters Patent No. 67,108, dated July 23, 1867.

To all whom it may concern:

Be it known that I, CLARK FISHER, a first assistant engineer in the Navy of the United States, of Trenton, in the county of Mercer and State of New Jersey, have invented a new and useful Mode of Burning Petroleum and other Hydrocarbon Liquids for the Production of Heat and Light, of which the following is a specification:

The nature of my invention consists, first, in so placing the apparatus, relatively to the heat produced, that it (the apparatus) will not be subjected to the action of the heat, and will, consequently, not be liable to be stopped up or rendered unserviceable by the deposition of solid carbon or of tar, which depositions I have discovered, by extensive experiments, always follow when the apparatus is itself subjected to heat; second, in the employment of a jet of steam for delivering the liquid hydrocarbon in the form of spray for combustion, the use of the steam being to atomize or separate the liquid hydrocarbon into extremely small particles, and to thoroughly mingle them with atmospheric air, the air being introduced, in the case of a steam-boiler, partly through grate-bars or perforated plates, and partly by means of a current induced by the action of the steam-jet itself; third, in the adaptation of means of adjusting the relative quantities of steam and liquid hydrocarbon used, so as to obtain the best economic result from the two materials as a whole.

I regard the steam used in this operation not as a combustible itself or supporter of combustion, but as performing two important mechanical functions—one in breaking the liquid hydrocarbon up into minute divisions or spray, and the other in inducing a current of atmospheric air to the same place of combustion with these minute particles of liquid hydrocarbon.

To enable others skilled in the art to make and use my invention, I give the following full, clear, and exact description thereof, reference being had to the accompanying drawings, making a part of the specification, in which—

Figure 1, *a* and *b* are front view and vertical section, respectively, of a common form of boiler, having four of my jet apparatus applied

to each furnace. Fig. 2, *c* is a section through the axis *xx*, Fig. 3, of one of my jet apparatus; and Fig. 2, *d* the same viewed in the direction of its axis. Fig. 3 is a plan view of the apparatus with the air-tube *C* detached.

Referring now to Fig. 2, *A* is a nozzle, whose upper part receives the steam, which, turning at right angles, discharges through the hollow conic frustum *A'* into the air-tube *C* in the direction *yy* of the axis of *C*. Within the hollow conic frustum *A'* is another hollow conic frustum, *B*, and the axes of both frustums are in the same straight line *yy*.

B can be screwed forward or backward in *A'* by means of the screw-thread, where it (*B*) passes through the back or closed end of *A'*. Some of the exterior surface of *B*, when screwed as far forward as possible, touches some of the inner surface of *A'*, thereby preventing any discharge of steam into *C*. By screwing *B* backward from this position an annular jet of steam is discharged, of any thickness of annulus desired. The expenditure of steam of given pressure is thus regulated, while the velocity of its efflux remains undiminished.

Through the center of the whole length of *B* is the channel for the passage of the petroleum or hydrocarbon liquid used. The expenditure of this liquid is regulated by a cock or valve, of ordinary construction, in the pipe connecting the outer end of *B* with the reservoir containing the liquid. A similar cock is also placed, for convenience, in the steam-pipe attached to *A*; but when the expenditure of steam is thus regulated, instead of by screwing *B* backward or forward, the velocity of its efflux from *A'* is diminished, and a less economic result obtained.

To obtain a more thorough mixture of the liquid hydrocarbon with the atmospheric air, whereby a more rapid and perfect combustion is caused, I employ the air-tube *C*, which is a hollow conic frustum of proper diameter and length. This air-tube surrounds the jet issuing from *A'*, and has its axis in the same straight line with that of *A'*. Its use is to retain and properly direct the current of atmospheric air induced by the jet of mingled steam and hydrocarbon liquid rushing from *A'*, thereby more effectually mixing the liquid hydrocarbon spray with the atmospheric air, thus put-

ting it in the best condition for rapid and perfect combustion.

The *modus operandi* of my invention is that steam, being admitted through A and A', surrounds, as an annulus, B, and induces, through B, a current of liquid hydrocarbon, which liquid the steam atomizes, or breaks up into the form of very fine spray, and projects the same forward into the chamber or place where the combustion is effected. The mixed current of steam and liquid hydrocarbon induces a current of atmospheric air, which is projected with them through C into the chamber where the combustion is effected, and which combustion it makes more rapid and more perfect. Additional air can also be supplied from independent sources, as through the grate-bars and holes in the furnace-door and front of a steam-boiler.

The entire apparatus is exterior to the chamber or place where the combustion is effected, and, being not subjected to heat, is not rendered unserviceable by the deposition in it of tar or of solid carbon.

I am aware that mixtures of hydrocarbon vapor and steam, and of hydrocarbon vapor,

steam, and air, have been used before, but with the apparatus subjected to the heat of the combustion, and, consequently, soon rendered unserviceable by the deposition of tar and solid carbon in it.

Having thus described my invention, and the mode substantially in which I contemplate its application, what I claim, and desire to secure by Letters Patent of the United States, is—

1. The apparatus, substantially as described.
2. The location of the apparatus outside of the chamber where the combustion is effected, so that it may not be affected by the heat of the same.
3. The method of regulating the supply of steam by the screwing outward or inward of B.
4. The delivery of liquid hydrocarbon for combustion in the form of spray by means of a jet of steam, substantially as herein described.

CLARK FISHER.
